CLAIM

What is claimed is the ornamental design for a candle holder, as shown and described.

DESCRIPTION

FIG. 1 is a perspective view of a candle holder showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing a candle in FIGS. 1 and 7 are included for the purpose of illustrating the invention in use, and form no part of the claimed design.
